BOTTLE CARRIER

Shade Wesley Turner, Danville, Ky.

Application February 7, 1946, Serial No. 646,011

4 Claims. (Cl. 294—87)

1

This invention relates to improvements in bottle carriers.

The primary object of this invention is the provision of a relatively simple type of bottle carrier which includes a frame and handle structure permitting of the ready placement of bottles within the carrier and the lifting of the same thereby without the necessity of individually handling each bottle.

A further object of this invention is the provision of an improved bottle gripping construction for bottle carriers.

A further object of this invention is the provision of a relatively simple bottle carrier construction, the parts of which may be economically fabricated and which may be utilized for the fast handling of soft drink beverages and the like.

Other objects and advantages of the invention will appear in the following detailed description.

In the accompanying drawing forming a part of this specification, and wherein similar reference characters designate corresponding parts throughout the several views,

Figure 1 is a perspective view of the improved bottle carrier.

Figure 2 is a side elevation of the bottle carrier.

Figure 3 is a view showing the parts arranged for reception of a bottle in the carrier.

Figure 4 is a cross sectional view showing the manner in which the bottle is locked in the carrier.

In the drawing, wherein for the purpose of illustration is shown only a preferred embodiment of the invention, the letter A may generally designate the improved bottle carrier. It preferably consists of a rigid frame structure B having bottle gripping jaws C and D pivotally connected together by a shaft arrangement E to which is connected a handle F.

The entire construction may be made of metal, plastic or the like and all parts are preferably of rigid material.

The frame structure B preferably consists of elongated parallel side bars 10 and 11 connected to right angled shorter end bars 12 and 13. All of these bars are straight and the end bars have jaw guide bars 20 connected at their ends by downturned portions 21 which may be welded or otherwise secured to the end bars. Intermediate their ends each of the bars 20 are provided with lugs or stop portions 23 at each side of the longitudinal center of the frame, and together with the portions 21 define guide slots 26 and 27 for guiding the movement of the jaws C and D.

2

The jaws C and D are identical. Each of them consists of a straight bar or rod or frame portion 40 having the ends thereof slidably disposed in one or others of the slots 26 or 27 at each end of the frame B. A bottle neck receiving frame bar or structure 41 is furthermore provided as a part of each bottle gripping jaw C and D defining neck receiving openings 42, the sides of which relatively slope divergent to the entrance to the opening in a direction away from the bar 40. This frame portion 42 is welded to the member 40 at each point 46, and the openings 42 face outwardly in the direction of the bars 10 and 11 of the frame structure B.

15 The connecting shaft E provides a pivot connection for the jaws C and D; the latter at each end having extensions 50 provided with loop portions 51 at their free ends journaled upon the shaft E.

20 It is noted that the shaft E is of a length equivalent to the overall length of the frame B, so that the ends of the shaft E lie beneath the side bar or frame portions 12.

25 The handle structure F includes the side portions 60 connected by a bight 61 to which a roller 62^a may be connected; the lower ends of the side portions 60 being laterally turned at 62 and fixedly connected, as by welding, at 64 to the shaft E at the inner sides of the bearing portions 30 51 of the jaws C and D.

35 With the operator carrying the bottle carrier in his hands (empty) it is necessary to lower the same over a case of bottles and by pressing downwardly the jaws C and D will swing open to the position shown in Figure 3 and permit the tops of the bottles to enter the openings 42 between the same and the frame side bars 10 and 11. Merely by then lifting upward upon the handle the shaft E will be pulled upwardly and 40 move the gripping jaws C and D laterally into the neck clamping position upon the bottle shown in Figure 4. The operator may then lift the bottles from a case.

45 The handle shown in the dot and dash positions of Figure 4 assumes this position by gravity and when it is so laterally positioned the gripping jaws or portions C and D will still remain in bottle clamping position. To remove a bottle it is merely necessary to press downwardly upon the handle 50 and the bottle may readily be removed, as is quite obvious.

The distance designated by "x" in the drawing shows the extent of opening of the bottle gripping portions of the jaws relative to the bottle gripping bars of the frame B for entrance of a bottle to

the carrier, and the distance designated at "y" is the bottle gripping distance between these same parts.

Various changes in the shape, size and arrangement of parts may be made to the form of invention herein shown and described without departing from the spirit of the invention or the scope of the following claims.

I claim:

1. In a bottle carrier the combination of a frame including elongated side bar portions and end portions connecting the same, a pair of bottle gripping frames, means pivotally and slidably connecting said bottle gripping frames upon the first mentioned frame; said bottle gripping frames having bottle neck receiving openings therein facing the side bar portions of said first mentioned frame in bottle gripping relation therewith, a handle, and a common pivot shaft pivotally connecting said frames together at the under side of the plane of said first mentioned frame, said handle being connected to said pivot shaft.

2. In a bottle carrier the combination of a substantially rectangular frame including end bar portions and side bar portions, a pivot shaft, a pair of bottle gripping jaws pivotally connected to said shaft and having laterally opened bottle neck receiving sockets facing the side bar portions of said frame in bottle gripping relation therewith, and handle means connected with said shaft for moving the same transversely with respect to the plane of said frame for opening or closing said jaws with respect to the side bar portions of said frame.

3. In a bottle carrier the combination of a substantially rectangular frame including end bar portions and side bar portions, a pivot shaft, a pair of bottle gripping jaws pivotally connected

to said shaft and having laterally opened bottle neck receiving sockets facing the side bar portions of said frame in bottle gripping relation therewith, handle means connected with said shaft for

5 moving the same transversely with respect to the plane of said frame for opening or closing said jaws with respect to the side bar portions of said frame, and means slidably and pivotally connecting said jaws to the end bars of said frame.

4. In a bottle carrier the combination of a supporting frame having bottle gripping portions at opposite sides thereof, a bail-like handle structure, bottle gripping jaws pivoted to the lower portion of the bail-like handle structure remote from a hand grasping portion with the bottle gripping jaws extending at opposite sides of the plane of the handle structure towards the bottle gripping portions of the frame, and means slidably and pivotally connecting said bottle gripping jaws

15 upon the frame intermediate the ends of said jaws and spaced from the pivots of the jaws upon the handle whereby upon movement of the handle transverse to the plane of the frame the jaws will be relatively moved upon the frame for opening 20 and closing relation of the bottle gripping portions of said jaws and frame.

SHADE WESLEY TURNER.
